United States Patent Office

Des. 231,623

Patented May 7, 1974

231,623

DOLL

Marvin I. Glass and Kathy A. Dunn, Chicago, Ill.,
assignors to Marvin Glass & Associates

Filed Jan. 8, 1973, Ser. No. 322,078

Term of patent 14 years

Int. Cl. D21—01

U.S. Cl. D34—4 R

FIG. 1 is a front elevational view of the doll embodying our design;

FIG. 2 is a side elevational view of the doll;

FIG. 3 is a rear elevational view of the doll;

FIG. 4 is a top view of the doll; and

FIG. 5 is a bottom view of the doll.

We claim:

The ornamental design for a doll, as shown.
